GIRDLE

Louis Melnick, New York, N. Y., assignor to Knit-craft Foundations, Inc., New York, N. Y., a corporation

Application July 12, 1952, Serial No. 20,591

Term of patent 7 years

(Cl. D20—2)

To all whom it may concern:

Be it known that I, Louis Melnick, a citizen of the United States of America, and a resident of the city of New York, in the county of Kings and State of New York, have invented a new, original, and ornamental Design for a Girdle, of which the following is a specification, reference being had to the accompanying drawing, forming a part thereof.

Fig. 1 is a front view of a girdle, showing my new design; and

Fig. 2 is a rear view thereof.

I claim:

The ornamental design for a girdle, substantially as shown.

LOUIS MELNICK.
